LARGE POWER ULTRA SHORT WAVE
GENERATOR

Hans Erich Hollmann, Berlin, Germany, assignor
to Telefunken Gesellschaft für Drahtlose Tele-
graphie m. b. H., Berlin, Germany, a corpora-
tion of Germany

Application June 30, 1933, Serial No. 678,486
In Germany June 30, 1932

3 Claims. (Cl. 250—27.5)

For the purpose of producing ultra short waves of large power, it has been known to provide an electron discharge device generator which distinguishes itself from standard transmitter equipment by having the electrodes of the device provided at both ends with energy supply leads, and the device itself at both of its ends with a tunable parallel wire (Lecher) system. The assemblage then acts as a single energy line which oscillates with one or more half waves, with the oscillator being disposed in the potential loop or anti-node.

In order that very large powers may be obtained, the customary method, i. e. to enlarge the oscillator valve, is impracticable, whenever ultra short waves are dealt with, because the wave length is directly related with the valve dimensions. For this reason, the only solution for the problem of obtaining a large power output has been to parallel a plurality of individual generators or oscillators, or else to raise the load per unit of the electron discharge device, and this has been made possible by cooling the electrodes by a fluid or a gas.

Now, according to the present invention, when using a scheme of this kind, special advantages are obtainable by using the tuning systems connected at both ends of the device for the purpose of supplying and draining (inlet and outlet) of the chilling liquid. For this purpose, the parallel leads should consist of tubes, and the same should be so connected with the electrodes which are also designed to be provided with cooling tubes, that the chilling liquid may flow therethrough unobstructed.

One embodiment of the invention is illustrated in the attached drawing. Referring to the latter, R designates the oscillator electron discharge device which has a filament K, a grid G and a plate A. In order to absorb the thermal load and to carry the same off by way of a chilling tube, the grid, which in the scheme predicated upon electron reversal principle (retarding scheme) is called upon to absorb the whole loss energy, is made of a special form of construction. It consists of a cooling tube T upon which are fitted in radial planes metallic rings r , r' , r'' , r''' which by supplemental longitudinal stays L, L', L'' may be further anchored and supported. The arrangement is also provided with a cooling tube T' which is designed to insure adequate abduction of heat.

Now, upon both ends of this oscillator or generator device, there are mounted the two Lecher wire systems D and D' which consist of two leads 55 and the tuning bridge pieces C and C', respec-

tively. According to this invention, the said Lecher leads or "wires" are tubular and these are so united with the cooling tubes T and T' of the electrodes that the chilling fluid or liquid can easily flow therethrough. Inasmuch as the said Lecher wires at the same time conduct or carry the electrode potentials, it is preferable to employ for the cooling an insulating liquid, such as oil, or a gas. In order that cracking or bursting of the glass body of the device R may be precluded as a result of expansion of the chilling tubes T and T', glass springs F are provided at least at one end designed to compensate for such slight changes in length as may happen in the electrodes.

It will be evident that the idea underlying this invention is similarly applicable to types of electron discharge device equipped, for instance, with two or four electrodes. It is likewise applicable and useful in multiple unit types of device 20 schemes in which several devices in sequence or series are aligned on a joint energy line. In such case, all of the devices may be traversed by the chilling fluids sequentially.

I claim:

1. An ultra short wave electron discharge device oscillation generator comprising an envelope having therein grid, anode, and cathode electrodes, and an oscillatory circuit comprising two parallel energy supply leads extending through said envelope and connected to said anode and control electrodes respectively for supplying energy thereto, another oscillatory circuit comprising the extension of said two energy supply leads through said envelope, said leads being in the form of hollow tubes for accommodating cooling fluid for the grid and anode electrodes of said generator.

2. An ultra short wave oscillation generator comprising an electron discharge device having grid, anode and cathode electrodes, a hollow tube extending through both ends of said device and connected to said grid for supplying said grid with potentials and for cooling said grid with a fluid flowing through said tube, another hollow tube parallel to said first tube and also extending through both ends of said device, said last tube being connected to said anode for supplying said anode with potential and for cooling same, and a capacitive bridge connected across said two tubes and forming therewith an oscillatory circuit.

3. An ultra short wave oscillation generator comprising an electron discharge device having grid, anode and cathode electrodes, said grid

being in the form of a plurality of metallic rings surrounding said cathode and positioned in parallel planes, a hollow tube extending through said device to supply said grid rings with potential and supporting said grid, another hollow tube parallel to said first tube and supporting said anode

and supplying said anode with a suitable polarizing potential, said tubes being respectively adapted to supply cooling fluid to said grid and anode, and a bridge across said tubes constituting therewith an oscillatory circuit.

HANS ERICH HOLLMANN.
